(57) **CLAIM**

The ornamental design for a mirror with stand, as shown and described.

DESCRIPTION

FIG. 1 is a front view of the mirror with stand, showing the mirror separated from the stand;

FIG. 2 is a back view thereof;

FIG. 3 is a right side view thereof;

FIG. 4 is a left side view thereof;

FIG. 5 is a top view thereof;

FIG. 6 is a bottom view thereof;

FIG. 7 is a top view of the mirror with stand, showing the stand separated from the mirror;

FIG. 8 is a bottom view thereof;

FIG. 9 is a front side view thereof;

FIG. 10 is a back side thereof;

FIG. 11 is a right side view thereof;

FIG. 12 is a left side view thereof;

FIG. 13 is a top perspective view of the mirror with stand; and,

FIG. 14 is a top perspective view of the mirror with stand, showing the stand separated from the mirror.

The broken lines depict portions of the article that form no part of the claimed design.

The mirror and base have been shown separated in some figures to show aspects of the design that are not visible when combined.

1 Claim, 14 Drawing Sheets
